UNITED STATES PATENT OFFICE.

JOHN KRAUSE, OF SAN FRANCISCO, CALIFORNIA.

DESIGN FOR A PIN.

46,532.

Specification for Design.

Patented Oct. 13, 1914.

Application filed August 5, 1914. Serial No. 855,329. Term of patent 3½ years.

To all whom it may concern:

Be it known that I, JOHN KRAUSE, a citizen of the United States of America, residing at San Francisco, in the county of San Francisco and State of California, have invented a new, original, and ornamental Design for Pins, of which the following is a specification, reference being had to the accompanying drawing, forming part thereof.

Figure 1 is a front elevation of a pin showing my new design. Fig. 2 is a vertical section.

I claim:

The ornamental design for a pin as shown.

JOHN KRAUSE.

Witnesses:

MARTIN NEIBES,
FRANK PORZER.
